METHODS OF AND APPARATUS FOR RENDERING VISIBLE MAGNETIC AND ELECTRIC FIELD PATTERNS

Gustav Fries, Ostheim, Kreis Hanau (Main), Germany, assignor to Julius Cato Vredenburg-Inglesby, London, England

Application September 24, 1951, Serial No. 248,064

Claims priority, application Germany September 27, 1950

6 Claims. (Cl. 178—6.6)

It is well known that one can obtain a clear picture of magnetic fields by placing iron filings in the vicinity of a magnet.

Another more recent method, described in U. S. A. periodical "Life" of January 3, 1949, is based on the luminous effect produced by a flow of electrons in a tube filled with mercury vapour. However, in order to render the pattern of a magnetic field visible by these methods, relatively powerful magnets are required.

Another method, which likewise became known in the U. S. A. in 1949, is based upon the electromagnetic shadow effect. According to this method there is superimposed in an electron microscope upon the electron shadow of, for example, a wire magnetised with speech frequencies by means of a magnetoacoustic device, the electron shadow of a fine wire net, and thereby distortions of the shadow image of the wire net are produced, the meshes of which are otherwise regular (periodical "Umschau" published by Umschau-Verlag, Frankfurt-on-Main, Germany No. 5, 1950, page 155). This method can only be carried out in a high vacuum and supplies black-and-white images.

It is an object of the present invention to render magnetic fields or electric charge patterns visible without it being necessary for these fields to be strong or for the carrier of the magnetism to be placed in a high vacuum; another object is to reproduce magnetic fields of different strength or electric charges of different potential by graduation in brightness according to their value.

According to this invention the magnetic or electric charge pattern are placed in the proximity of an electron-field's emitting surface, for example, of a photo-cathode. It has been found that in this manner the electron emission of said surface is modified in accordance with the pattern of the magnetic field distribution or the electric charge pattern, thus transforming the same into an electron image which can be rendered visible in various ways well known to those skilled in the art. According to a preliminary explanation, in this manner the energy required for releasing electrons from the photo cathode is influenced or controlled, and accordingly if the electron image produced on the photo cathode is emitted, accelerated and focused upon a luminous screen by an electron-optical device, the pattern of the magnetic fields or electric charges becomes visible on this luminous screen.

In order that the invention may be more readily understood, various aspects and embodiments will now be described with reference to the accompanying drawing.

Figs. 1 and 3 illustrate one form of apparatus,

Fig. 1 being a back elevation showing only certain elements, including the luminous screen,

Fig. 2 is a somewhat diagrammatic view, partly in perspective and partly in sectional elevation, while

Fig. 3 is a front elevation taken on section line A—A of Fig. 1, showing certain elements only,

2

Figs. 4—8 are representations of the luminous screen under different conditions,

Fig. 9 is a somewhat diagrammatic side elevation of a form of apparatus suitable for transforming magnetic oscillations into oscillations of light,

Fig. 10 is a diagrammatic perspective view, partly in section, of one form of apparatus for producing on a strip-like carrier cinematographic series of magnetic records of two-dimensional optical phenomena.

10 Fig. 11 is a schematic section on line C—D of Fig. 10. Figs. 12 and 13 show, in two elevations at right angles to each other, a detail of the apparatus of Fig. 10.

Fig. 14 shows diagrammatically a form of apparatus for reconverting cinematographic series of field-pattern 15 or other picture records into visible cinematographic pictures, and

Fig. 15 is a section on line E—F of Fig. 14.

Referring now first to Figs. 1 to 4. The bundle of light rays 2 coming from a source 1 is directed upon a 20 lens 4 through optical means 3, and through this lens a beam of parallel light rays 5 is radiated upon the photo cathode 6 which is applied within the evacuated glass vessel 9 upon a metal layer semi-transparent to light. If a line grid 7 and, for example, a steel band 8, are 25 interposed in the path of the light beam 5 between the lens 4 and the photo cathode 6, an electron-optical shadow image 13 (Fig. 1) is produced upon the luminous screen 11 when the electron-optical device 10 is supplied with electric voltage from the source 12.

30 If now, for example, a permanent magnet 14 is placed upon the steel band 8 with its poles 15 and 16 bridged by the steel band, the latter becomes locally magnetised. When the band is brought before the photo cathode 6, the magnetic field recorded at this point on the steel band 35 8 then influences the energy required for releasing the electrons leaving the photo cathode 6 so that an electronic image corresponding to Fig. 4 becomes visible upon the luminous screen 11.

30 This method may be modified by also activating that part of the photo cathode 6 which is situated in the optical shadow of the steel band 8 when the latter is illuminated by the beam of light 5. For this purpose a source of light 17 may be provided which illuminates the photo cathode 6 from its back through optical means 18. Since

45 now the shadow 13 of the steel band 8 (Figs. 1 and 4) is illuminated, the image obtained on the luminous screen (Fig. 4) is modified correspondingly into an image as shown in Fig. 5. In this the shadow 13 of the steel band 8 is no longer visible, and the image now only constitutes the cathode image of the pattern of the magnetic field.

50 It can be verified by the image obtained that by stroking the steel band 8 with a permanent magnet 14, the previous magnetic impression can again be erased. It is true that in this case magnetic lines of force can still be found at the two ends of the band 8. However, the band can also be entirely de-magnetised by means of the permanent magnet 14 if the magnet is approached and removed step by step while being moved over the band, 55 as can be demonstrated by means of the apparatus shown in Fig. 2.

60 This form of apparatus therefore constitutes a useful means for demonstrating and examining magnetic phenomena.

65 Another application of particularly great practical importance is illustrated in Fig. 9, in which, for example, the recording head 19 of a magnetic recorder is arranged in front of the photo cathode 6 so that the gap 20 of the recording head faces the photo cathode. In this case images on the luminous screen 11 (Fig. 2) are

70 produced as shown in Fig. 7: Shadow image of the recording head 19 (Fig. 9) when not talked at, while

Fig. 6 shows the shadow image of the recording head 19 when talked at. It can be seen how the magnetic field at the location of the gap builds up and collapses. If the photo cathode 6 is additionally illuminated by the source of light 17 through optical means 18, then the image on the luminous screen assumes the form shown in Fig. 8. Since the recording head 19 is supplied with alternating currents, these images on the luminous screen change periodically in accordance with the frequency of the current and therefore are advantageously observed through a stroboscope mirror, thus resolving the generation and disappearance of the image of the magnetic alternating field into part-images, but preferably the whole phenomenon is cinematographically recorded in the manner of slow-motion pictures.

By the method and apparatus described not only magnetic fields but also electrostatic fields can be rendered visible. If, for example, a suitable carrier 8 to which electric charges have been applied is placed in front of the photo cathode 6 instead of a steel band, the location of the electric charges on the carrier becomes also visible upon the luminous screen 11.

In this manner recordings obtained by the method of "Electrography" (Zeitschrift fuer Technische Physik, volume 16, issue 12, 1935, pages 607-614) may be rendered visible.

A further feature of the present invention consists in accelerating the whole photo cathode image to such an extent that it leaves the high vacuum in the form of cathode rays through a Lenard window (similar to the window 26 hereinafter described with reference to Figure 10) so as to strike and charges electrically the whole of an image surface on a carrier film of insulating material which is placed outside the Lenard window. Since, however, an electric charge image normally does not adhere for long in the atmosphere, according to another feature of the invention an image recording is effected by magnetising a magnetisable layer applied upon a carrier.

Fig. 10 shows one form of suitable apparatus for the recording of moving pictures upon a magnetisable carrier 42, while Fig. 14 shows one form of apparatus for reproducing such magnetic image recordings. The latter apparatus can also be employed for the large-screen projection of photographic moving pictures and of television pictures. The recording of the moving pictures as shown in Figure 10 is effected by causing the lens 21 to form upon the photo cathode 22 a stationary image of the scene to be recorded, thus producing an electron image on the photo cathode. This electron image is accelerated from the photo cathode 22 by the anode 23 having positive electric bias and is focused upon this anode with high definition by a coil 24 which acts as a magnetic lens. The anode 23 itself is provided with a slot-like opening 26 which has the width of the image and such a fraction of its height as corresponds to the number of lines into which it is intended for the image to be dissected. Assuming, in accordance with dimensions usual in cinematography, that the electron image of the photo cathode 22 formed on the anode 23 has a width of 88 mm. and a height of 76 mm., then the height of the opening 26, assuming dissection of the image surface into 1000 lines, would have to be 0.076 mm.

The electron image coming from the photo cathode 22 is further swept in saw-tooth fashion to move vertically past the slot opening 26 of the anode 23 by a pair of deflector coils 29 and 30 (shown in broken lines) which is supplied with a saw-tooth sweep current from an electric battery 32 through a rotating potentiometer 31. In this manner periodically parts of the electron image pass line by line through the slot opening and through a second anode 34 at a higher voltage, which is likewise provided with a slot 33, to strike upon col-

lector anodes 35 provided behind the anode 34 in multiple arrangement. (In order not to complicate the drawing, only ten collector anodes 35 are shown in Fig. 10.) These collector anodes 35 are distributed over the width of the line and sub-divide the line into image points. In the assumed example of dissection of an image into 1000 lines with 76 mm. image height, on the width of the line of 88 mm. with a spacing of 0.01 mm. roughly 1158 collector anodes of this kind would have to be provided so that the number of the points into which the image area could be resolved would be 1,158,000. Since, however, in cinematography and television twenty-five images must be transmitted in a second, the image point frequency to be recorded in each second would accordingly be 28,950,000. Although it used to be quite impracticable to record such a high frequency magnetically by magnetising a magnetisable carrier recent discoveries bring this within the range of the possible, since a magnetic tone carrier with a reflecting surface has successfully been produced in which the thickness of the magnetisable layer may be less than one thousandth of a mm. (1μ) and which has very good magnetic qualities.

The electrons impinging upon the collector anodes 35 control amplifier tubes 36 and 37 associated with each collector anode (only two have been illustrated in the example). The anode current of these tubes is thus modified with the brightness value of the image points, and its A. C. component is conducted through condensers 38 and 39 to recording magnets 40, 41, etc. These magnets are placed side by side in a line and are in contact with the carrier 42 to be magnetised. Since each of these recording magnets has only to record one point on the image line, it has to deal, in the 1000-lines example, with a frequency of 1000 per image or, in the case of 25 images per second, with a frequency of 25 kc. per second, a frequency which is well within the range of possibility and can readily be accommodated on a carrier length of 45.6 cm. It is thus possible for a carrier film having a layer of magnetisable material in the size of the usual 35 mm. standard cinema film to be used for the image recording. For a 1000-line resolution of the image field of 19 x 22 mm. with standard film size there is only, for the time being, the difficulty of accommodating in a line 22 mm. long as many as 1,158 recording magnets side by side, as is shown in Fig. 13. In this case each magnet, assuming an anti-magnetic spacing layer of only 1000th of a mm., would be roughly 0.018 mm. wide.

Practical experiments of magnetic image recording according to the invention have, however, already been carried out successfully with lower numbers of image points. In these the image size upon the carrier band of 35 mm. width was 19 x 22 mm. and on a line there were 40 magnets arranged side by side with interposed anti-magnetic spacing layers of 0.05 mm., so that the image resolution with square arrangement of points was $38 \times 40 = 1,520$ points. This in fact is already more than was usual in the first television transmissions in 1930.

It remains to be described on the recording side how the magnetisable carrier is moved past the recording head 40, 41, etc. The carrier 42 is arranged in a known manner upon a supply spool 43, is withdrawn from the latter past a roller 44 and the recording head 40, 41 by means of a toothed drum 45, and is then wound upon a second spool 46. The toothed drum 45 is driven by a motor 47 through a worm 48 and worm-wheel 49 so that in the example referred to the 35 mm. carrier 42 moves with the normal speed of 45.6 cm. per second corresponding to 25 frames per second. Accordingly the slide contact S1 of the potentiometer 31 is driven by a gear wheel 50 through a pinion 52 and thus produces the required sweep current for the pair of coils 29 and 30 synchronously with the frame change and with the continuous movement

of the carrier. As a result the electron image, and consequently the magnetic image being recorded, will be stationary, during each frame-sweep period, relative to the moving carrier, on which it will thus be recorded progressively as the carrier moves past the recording magnets. Then during the fly-back period of the sweep the electron image is moved back so as to advance on the carrier by the length of a frame. Fig. 11 is a section on line C—D, Fig. 10, of the electron image tube 53.

Simultaneously with the magnetic recording of the image, the magnetic recording of the sound upon the carrier 42 is effected through a microphone 54, amplifier 55 and magnetic recording head 56, so that, immediately after recording, both the image and the sound are adapted to be reproduced. This possibility is of particular importance in sound film studios for the instantaneous checking of picture and sound after shooting. It also provides a method of rapid transmission for television reporting, for example, when it is necessary for the reporting to be stored temporarily while the transmitter is radiating some other transmission.

Apparatus suitable for the reproduction and large-screen projection of the magnetically or electro-statically recorded images is illustrated by way of example in Fig. 14. In this case the carrier 57 upon which the recording has been made, for example, an electrostatic image and sound recording, is continuously withdrawn from the supply spool 68 via rollers 59 and 60 by means of the toothed drum 58. In this movement the carrier 57 passes at a uniform speed a photo cathode 61, which is illuminated from the inner side by a source of light 62 through lens system 63 and is thereby caused to emit electrons. The photo-electric layer of the photo cathode is so large as to be simultaneously influenced by two electrostatic images 64 and 65. The two electron images produced in this manner are accelerated towards and focussed through an electrostatic optical device 67 upon a layer 164, which is adapted for secondary emission and which is applied upon a thin metal partition wall 25 which, similarly to a Lenard window, is pervious to accelerated electrons. The metal film 25 need not, however, be supported by a grid as in the case of a Lenard window, since it is located wholly within the high vacuum space of the tube 162 and therefore is not exposed to unilateral pressure. The focus coil 70 causes the electron image or secondary electron image coming from 164 to be directed with sharp definition and without diffusion, in a second stage, upon a further emission layer 71, which is provided on a further metal skin 72 biased with a higher voltage than the metal skin 164 so that the electron image is once more accelerated on its way to layer 71. In a third stage, i. e. between emissive screens 72 and 73, electron-optical equalisation is effected in the form of a saw-tooth periodic sweep to compensate for the image movement due to the movement of the carrier 57 and thus obtain a further image 88 which is now stationary. To this end, while the electron image coming from the screen 72 is once more projected with sharp definition upon the metal film constituting screen 73 by means of the focus coil 75, at the same time the electron image representing two consecutive images placed above one another, is periodically swept upwardly by means of a saw-tooth sweep current supplied to the deflector coils 76 and 77 (see also Fig. 15, which is a section on line E—F of Fig. 14), synchronously with the movement of the image carrier 57 in such manner that the image 88 appears stationary at the middle of the screen 73. The length of each sweep period is equal to the time which the carrier takes to move forward by one frame pitch, so that after this period the next following frame on the carrier will be projected, thus producing the well known cinematograph effect. The sweep current is supplied to the deflector coils 76 and 77 from a battery 80 through the sliding contact 78 of a potentiometer 79 which rotates

synchronously with the movement of the image carrier. The sliding contact 78 itself is driven, similarly as in the recording apparatus (Fig. 10), through a gear wheel 81 and pinion 82, from the toothed drum 58, which itself is driven by motor 83 through a worm drive 84, 85.

This electron-optical equalisation of the movement of the two images 64 and 65 which are positioned above one another and which come from the moving image carrier 57 (see also Fig. 15) in relation to a stationary image upon 73, is an important feature of the invention. This equalisation is in principle also applicable during recording when for example the electron images are applied to a continuously moving image carrier as electric charge images without raster. The advantage of an electron-optical equalisation of the image movement as compared with mechanical equalisation (Mechau cine-projector) consists in the fact that an electron-optical sweep can be effected without inertia and extends upon the image line, whereas in the case of purely optical equalisation three images are required which in reproduction must be superimposed by mechanical means.

Now after the image field 83 of the electron image coming from 71 has been rendered stationary upon the emission electrode 73, it can in a subsequent stage be accelerated once more towards, and focussed by a coil 89 on to, a luminous screen 90 where it is transformed by the impact of the electrons upon the screen into a light image adapted to be projected by a lens system 74.

The reproduction of the sound associated with the sequence of images is effected in known manner, the sound track being scanned on the carrier 57 by means of a head 91, the output current of which is amplified in amplifier 92 and radiated as sound through loudspeaker 93.

The focus coils 70, 75 and 89, which are adjustably supplied with current from sources 94, 95 and 96 through the resistances 97, 98, 99, may be replaced by annular permanent magnets when an apparatus according to Fig. 14 has become standardised. In this case the sources of current with accessories become redundant. The same is also true for the focus coil 24 (Fig. 10) with the associated source of current 100 and adjustable resistance 101.

The apparatus according to Fig. 14 is also adapted for the projection of normal cinema films. In this case the photographic image film 102 is moved past the objective 103 and the illuminated image upon the film is projected through the objective 103 with sharp definition upon the photo cathode 61 where it is converted into an electron image, and the image amplifying and projecting procedure is the same as that described above in respect of magnetic or electrostatic images.

The apparatus is also adapted for the large-screen projection of television images. In this case a television receiver tube 104 is placed in front of the objective 103. This television tube may also be utilised for the illumination of the image film 102, for which purpose the screen surface of the tube 10 is arranged to be flooded by cathode rays.

I claim:

1. Arrangement for making visible magnetic field or electric charge patterns, comprising an evacuated envelope containing a photo cathode layer located close to a wall of the envelope, said photo cathode layer having a surface area sufficiently large to accommodate the pattern, means for substantially uniformly illuminating said photo cathode layer, means for supporting the element producing the pattern outside the envelope and so close to said wall as to influence differentially the electron emission from different points of the photo cathode layer in accordance with the pattern, and means for directing the electrons emitted from the photocathode layer on to an electron-sensitive surface which renders visible the pattern of the electron emission from said layer.

2. Arrangement as claimed in claim 1, comprising also a fluorescent screen within said envelope, and electron-

optical means for focussing the electron emission pattern from said photo cathode on to said fluorescent screen.

3. Method of making visible magnetic field or electric charge patterns, which consists in positioning the element producing the pattern in proximity to a photo-electric layer, flooding said layer with light of suitable wavelength to cause said layer to emit electrons in a distribution corresponding to the pattern, and accelerating and focussing the emitted photoelectrons on to a luminous screen to produce on said screen a visible image of the electron emission of said layer.

4. An image converter tube, comprising an evacuated chamber the wall of which includes an electron-pervious portion, and a photo cathode having a photo-emissive area arranged in said evacuated chamber in a position facing said electron-pervious wall portion, the wall of said chamber further including a transparent portion so arranged as to permit a light image to be projected therethrough on to said photo cathode.

5. An image converter tube, comprising an evacuated chamber the wall of which includes an electron-pervious portion, a photo cathode having a photo-emissive area arranged in said evacuated chamber in a position facing said electron-pervious wall portion, and means for imaging photo electrons emitted by said photo cathode on to and through said electron-pervious wall portion, the wall of said chamber further including a transparent portion so arranged as to permit a light image to be projected therethrough on to said photo cathode.

6. Apparatus for recording moving phenomena in the form of sequence of individual picture records on a tape-like carrier, comprising means for producing a stationary

5
10

optical image representing said phenomena, a photo-cathode for converting said optical image into an electron image, means for scanning the electron image line by line through a gap, a plurality of collector anodes arranged side by side along the length of said gap for sub-dividing each line of the electron image into image points, means for transmitting the output of the individual collector electrodes through amplifiers to the corresponding number of recording heads, said recording heads being arranged side by side, and means for continually feeding a tape-like magnetizable carrier past said array of recording heads whereby the image is recorded line by line on the carrier.
